United States Patent Office

Des. 203,240
Patented Dec. 14, 1965

203,240

HOLDER FOR VEHICLE REGISTRATION CERTIFICATES

Paul J. McCreary, 4621 Cortland Drive,
Corona del Mar, Calif.

Filed Feb. 16, 1965, Ser. No. 83,828

Term of patent 14 years

(Cl. D87—3)

FIG. 1 is a perspective view for a holder for vehicle registration certificates, embodying my new design;

FIG. 2 is a rear elevational view thereof, on a reduced scale;

FIG. 3 is a top plan view thereof;

FIG. 4 is a cross-sectional view thereof, taken on line 4—4 of FIG. 2;

FIG. 5 is a front elevational view thereof;

FIG. 6 is a left-side elevational view thereof;

FIG. 7 is a right-side elevational view thereof; and

FIG. 8 is a bottom plan view thereof.

I claim:

The ornamental design for a holder for vehicle registration certificates, substantially as shown.
